UNITED STATES PATENT OFFICE.

FRANK L. DEMARTINI, OF ST. LOUIS, MISSOURI.

TRAY-SUPPORT.

No. 817,301.

Specification of Letters Patent.

Patented April 10, 1906.

Application filed October 30, 1905. Serial No. 285,136.

To all whom it may concern:

Be it known that I, FRANK L. DEMARTINI, a citizen of the United States, residing at St. Louis, State of Missouri, have invented certain new and useful Improvements in Tray-Supports, of which the following is a full, clear, and exact description, reference being had to the accompanying drawings, forming a part hereof.

10 My invention has relation to improvements in tray-supports for trunks; and it consists in the novel construction of support more fully set forth in the specification and pointed out in the claims.

15 In the drawings, Figure 1 is a perspective of a trunk with tray swung open, showing my invention applied thereto. Fig. 2 is an enlarged view of the support turned to proper position to support the tray. Fig. 3 is a 20 similar view showing the supporting- rods disengaged from the trunk-walls. Fig. 4 is a sectional detail on line 4 4 of Fig. 3. Fig. 5 is a perspective of the clip or bearing for the outer end of the supporting-rod. Fig. 6 is 25 a perspective of a wardrobe-tray swung to open position and having its supporting-rods received by depressions in the trunk-walls. Fig. 7 is a vertical section on line 7 7 of Fig. 6, and Fig. 8 is a perspective of the grooved 30 casting for receiving the ends of the supporting-rods.

The object of my invention is to provide suitable means for temporarily supporting a trunk-tray while in an open position, the invention being specially applicable to the swinging tray hinged directly beneath the lid of a trunk, though, as presently to be seen, the device may with equal propriety be applied to any tray which when once opened would 35 have a tendency to close if left temporarily unsupported while in such open position. The tendency for a hinged tray to close after once being swung open is due to the weight of the contents of such tray, the said contents 40 shifting the center of gravity of the load well beyond the hinge-axis of the tray, and thus tending to close it if left unsupported.

The advantages of my improvement will be better apparent from a detailed description of the invention, which is as follows: Referring to the drawings, B represents the body of the trunk, and L the outer lid thereof. The trunk is provided with a tray T, hinged immediately beneath the lid, and when the lid is swung to an open position the tray may 45 be swung up against it. The weight of the

tray contents has a tendency to force the tray to a closed position, and if left unsupported the tray will close, and thus become a source of annoyance to one desiring access to the bottom of the trunk. The tray is supported by means of the following contrivance: Rotatably secured to the tray-bottom adjacent to the edge thereof is a disk or equivalent member 1, provided with an operating handle or wing 2, projecting beyond the edge of the disk, the latter having pivotally secured to one of its faces (preferably the outer face) the inner ends of the rods 3 3, the points of connection with the rotatable member being diametrically opposite to one another. By rotating the member 1 in proper direction the rods are either forced apart or retracted inwardly, as is obvious. The outer ends of the rods pass through suitable tapering guide-loops 4 of the clips or bearings 4', secured to the tray, as shown. After opening the tray the member 1 is given a turn in proper direction so as to bring the points of connection of the rods with the said member 80 in substantially a horizontal relation, the rods being by this movement forced outwardly, so as to cause their outer ends to overlap the upper edges of the adjacent vertical walls of the body of the trunk, the said overlapping portions thus temporarily supporting the tray-Fig. 1. To close the tray, the member 1 is given a turn in proper direction (see arrow, Fig. 2,) to draw the rods inwardly a sufficient distance to cause their outer ends to come 90 within the adjacent vertical walls of the trunk, Fig. 3, when the tray can be readily closed. In the form shown in Fig. 1 the pressure exerted on the rods 3 is substantially a vertical one, and the friction between their outer ends and 95 the supporting edges of the trunk-walls is sufficient to overcome any tendency on the part of the rods to slip along said edge; but in the case of a wardrobe-tray T', where from an excessive load the danger of slipping is imminent, the supporting-walls are provided with metal castings 5, Fig. 8, in which are formed suitable grooves or sockets 6 for receiving the rods. The walls of the sockets insure against 100 any possible slipping of the rods.

I am aware that trunk-trays have been provided with spring-actuated supports, but since these operate automatically upon the opening of the tray they lock the tray when in such open position. Should the person 110 using the trunk momentarily open the tray and forget about the automatic locking and

then suddenly close the tray, the supporting-
rods either become strained or bent and be-
come thereafter a source of annoyance. With
my improvement the tray may be opened
5 temporarily, and unless the person so desires
he need not bring the supporting device into
requisition and may close the tray without
danger of breaking or bending the rods, since
these cannot expand to a locking position un-
10 less positively actuated and only when occa-
sion for their use arises.

Having described my invention, what I
claim is—

1. In combination with a swinging trunk-
15 tray, a member rotatably mounted to the
bottom of said tray adjacent to the rear edge
thereof, rods pivotally secured thereto at
points diametrically opposite to one another
20 and extending in opposite directions along
said tray, suitable tubular bearings for the
free ends of said rods secured to the tray, the
ends of the rods being adapted to be forced
outwardly and overlap the edges of the adja-

cent trunk-walls for an oscillation of the rota-
25 table member in one direction, and to be re-
tracted inwardly for an oscillation thereof in
the opposite direction, substantially as set
forth.

2. In combination with a swinging trunk-
tray, a disk rotatably mounted to the bot-
30 tom of the tray adjacent to the rear edge
thereof, rods pivotally secured at their inner
ends to the disk on opposite sides of the cen-
ter thereof, guide bearings or loops for the
35 free ends of the rods carried by the tray, the
upper edges of the vertical walls of the trunk
adjacent to the outer ends of the rods being
provided with sockets for the reception of
said rods, the parts operating substantially
40 as, and for the purpose set forth.

In testimony whereof I affix my signature
in presence of two witnesses.

FRANK L. DEMARTINI.
